TRIM MOLDING

Lucien Péras, Billancourt, France, assignor to Regie Nationale des Usines Renault, Billancourt, France

Filed Sept. 6, 1962, Ser. No. 71,588

Term of patent 14 years

(Cl. D14—6)

FIG. 1 is a perspective view of the trim molding showing my new design;

FIG. 2 is a side elevation thereof; and

FIG. 3 is an end elevational view thereof.

The rear, not shown, is substantially plain.

I claim:

The ornamental design for a trim molding, as shown and described.
